UNITED STATES PATENT OFFICE.

HARRY A. JACKSON, OF FREMONT, IOWA.

CARRIER SYSTEM.

No. 903,382.

Specification of Letters Patent.

Patented Nov. 10, 1908.

Application filed May 29, 1907. Serial No. 376,352.

To all whom it may concern:

Be it known that I, HARRY A. JACKSON, citizen of the United States, residing at Fremont, in the county of Mahaska and State of Iowa, have invented certain new and useful Improvements in Carrier Systems, of which the following is a specification.

The present invention relates to means for transporting light packages or articles from one point to another, such as generally used in stores for carrying cash from the salesman to the cashier and returning change.

The present invention relates to systems of the character aforesaid in which a car is mounted to travel upon a track and is projected by means of an elastic or like throwing means.

The invention further relates to a single track and to means for maintaining the same under tension, thereby admitting of the car being projected or returned from either end of the track.

For a full understanding of the invention and the merits thereof and also to acquire a knowledge of the details of construction and the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a side view of a carrier embodying the invention. Fig. 2 is a top plan view of the propelling means at one end of the track. Fig. 3 is a transverse section on the line $x-x$ of Fig. 2. Fig. 4 is a side elevation of the means at one end of the track showing the car moved to place the propelling means under tension and about to be released.

Corresponding and like parts are referred to in the following description and indicated in all the views of the drawings by the same reference characters.

The track 1 may consist of a wire or cable and is stretched between terminal points and has an approximate horizontal position. The track is normally under tension and is movable linearly to admit of subjecting the propelling means to tension from either end of the track. A sprocket chain 2 froms a terminal portion of each end of the track and passes around a spring actuated pulley

or drum 3 to which it is connected. It is to be understood that each terminal, station or point of a track is similarly equipped, hence a detail description of one will apply and suffice for both. The pulley or drum 3 is mounted upon a shaft or axis 4, and upon said shaft or axis is loosely mounted a sleeve 5. A coil spring 6 has its outer end secured to the outer portion of the pulley or drum 3 and its inner end made fast to the sleeve 5. A ratchet wheel 7 fast to an end portion of the sleeve 5 is adapted to have its teeth engaged by a pawl 8 pivoted upon the supporting framework. By turning the sleeve 5, the coil spring 6 may be subjected to any desired tension, the sleeve being prevented from turning backward by engagement of the pawl 8 with a tooth of the ratchet wheel 7. It is to be understood that the coil springs of terminal pulleys or drums 3 are reversely or oppositely wound and tensioned, so that one counterbalances the other. When the parts are properly adjusted and the coil springs 6 under like tension, the track 1 occupies a medial position between the said pulleys or drums. The pulley or drum 3 is provided with two sets of sprocket teeth 9 and 10. The sprocket chain 2 coöperates with the teeth of the sprocket portion 9. An operating sprocket chain 11 passes over the sprocket portion of the pulley or drum provided with the teeth 10 and its end portions are loose in the front and in the rear of the pulley and terminate in hand pieces 12 and 13 to be pulled upon when operating the carrier.

The supporting frame comprises a horizontal portion 14 and a vertical portion 15, said parts being formed of transversely spaced bars which are arranged to come upon opposite sides of the pulley or drum. A hanger 16 is secured to the crown of the vertical portion 15 and is attached at its upper end to a ceiling piece 17. The hanger 16 may be a tube or rod. Braces 18 connect end portions of the vertical and horizontal portions of the drum. The supporting frame also embodies a rear extension 19 which embraces opposite sides of the pulley or drum and springs from the vertical portion 15 about in line with the axis of the pulley or drum. A guy 20 connects the rear end of the frame member 19 with the ceiling or other convenient support so as to brace and stay the same against the tension and strain upon the track. Grooved pulleys

21 are provided at the ends of the members of the horizontal portion 14 of the supporting frame and the propelling elastic or cord passes thereover.

5 The car 22 may be of any construction and is adapted to travel upon the track 1. A box or receptacle 23 has detachable connection with the car and is adapted to receive the article to be transported and may be of 10 any size and shape according to the special purpose for which the system is constructed. A catch 24 has connection with the sprocket chain 2 and is adapted to make detachable connection with the car 22. A trip 25 is arranged in the path of the rear end of the catch 24 to effect release of the latter from the car after the propelling means has been subjected to tension sufficient to cause the car to reach the opposite terminal to that 20 from which started. The catch 24 is fulcrumed to a block 26 to which the outer end of the sprocket chain 2 is connected in any substantial way. The propelling cord or elastic 30 may be of any length and is 25 doubled upon itself and has its end portions connected to the block 26 or to the outer end of the sprocket chain 2, the end portions of said cord or elastic passing over the pulleys 21 and adapted to have its bight to engage 30 with an end of the car 22. To reduce the shock incident to stoppage of the car at a station, the block 26 is provided with a buffer, the same consisting of a rod 27 passed loosely through a longitudinal opening of 35 said block, and having a rubber bumper at its front end and having a coil spring 28 interposed between said block and the head of the rod. To prevent displacement of the bumper a pin 29 is passed through a transverse opening in the projecting end of the rod 27.

When the parts are assembled substantially as shown in Fig. 1, the coil springs 6 are under tension, the one counterbalancing 45 the other. To propel the car from the left hand station in Fig. 1 to the right, the hand piece 13 of the operating sprocket chain 11 is drawn upon, thereby causing the pulley or drum to rotate to the right with the result 50 that the tension upon the spring 6 is reduced and the sprocket chain 2 at the left hand end is wound upon the pulley, thereby drawing the track to the left and increasing the tension on the coil spring 6 of the pulley at the 55 right. As the sprocket chain 2 is wound upon the left hand pulley 3, the car is drawn rearward, thereby subjecting the propelling cord or elastic 30 to tension, and when the catch 24 strikes the trip 25 and is released 60 from the car, the latter is shot forward by the action of the propelling means. Upon releasing the pull upon the hand piece 13, the pulley 3 at the left is returned to normal position by the superior tension of the spring 6 65 coöperating with the right hand pulley. The

track 1 is likewise returned to a given position. It will be understood that the track is under tension at all times, hence will not sag. Should it be required to return the car from the right hand station to the left hand station, the hand piece 12 at the left hand station is pulled upon, thereby causing the pulley or drum 3 to be rotated to the left, with the result that the coöperating spring 6 thereof is decreased in tension and the 70 sprocket chain 2 at the left is unwound. The spring coöperating with the right hand pulley turns the right hand pulley to the left and winds up the sprocket chain, with the result that the track 1 is moved to the right, being at all times under tension. The movement of the sprocket chain 2 at the right hand carries the car outward or to the right and subjects the propelling cord or elastic to tension, and when the catch is tripped the 80 car is shot forward from right to left. It is to be understood that the tension of the coil spring 6 is far in excess of the tension of the propelling cord or elastic 30, hence the unwinding of the spring 6 coöperating with one 85 pulley or drum effects a tensioning of the propelling means of the car when located to be projected from the end of the track adjacent to said pulley or drum.

The trip 25 is adjustable, thereby admitting of varying the tension of the propelling means according to the distance to be traveled by the car and the amount of force required to be exerted to drive the same from one station or terminal to the other. It is 100 also observed that the propelling cord or elastic 30 is doubled around the pulley 21 and that both ends are subjected to tension when winding the sprocket chain 2 upon the pulley at the end from which the car is to be 105 propelled. By subjecting both ends of the propelling cord or elastic to tension, the degree of movement of the car may be one-half that required if the pull were direct between the ends of the said propelling elastic.

The construction is such as to admit of the successful use of a single track and of propelling the car in either direction from either station, the track being under tension at all times, thereby supporting the car and enabling the same to be propelled with a minimum expenditure of driving force.

Having thus described the invention, what is claimed as new is:

1. In a carrier system, the combination of 120 supporting frames, a spring actuated pulley mounted upon each of said frames, a track having end portions connected to each of the spring actuated pulleys, means for operating the pulleys for moving the track longitudinally, fixed pulleys upon each of the supporting frames, a car movably mounted upon the track, elastic propelling members passing respectively around the fixed pulleys upon the respective supporting frames each 125 130

- of said elastic propelling members being secured to the track and passing around said pulleys and arranged to have the portion intermediate such pulleys engage the car, means at each end of the track for locking the car thereto and a trip carried by each of said supporting frames for automatically releasing the car from the track when the latter has been moved to place the elastic propelling member under tension.
2. In a carrier system, the combination of supporting frames, spring actuated pulleys mounted upon the respective frames, a track having end portions connected to the spring actuated pulleys, means for operating said pulleys to move the track longitudinally, a block secured to the track at each end thereof, a car movably mounted upon the track,

fixed pulleys carried by each of the supporting frames, elastic propelling members passing around the fixed pulleys of the respective supporting frames and secured to the track at one end, and arranged to have the portion intermediate such pulleys engage the car, a catch mounted upon each of the blocks for engaging the car to lock the same to the track, and a trip carried by each of the supporting frames for releasing the car when the track has been moved.

In testimony whereof I affix my signature 30 in presence of two witnesses.
